US00D912346S

(12) **United States Design Patent** (10) **Patent No.:** **US D912,346 S**
Lee et al. (45) **Date of Patent:** **** Mar. 2, 2021**

(54) **STAND FOR CLEANER**

(71) Applicant: **Samsung Electronics Co., Ltd.**, Suwon-si (KR)
(72) Inventors: **Hwandong Lee**, Seoul (KR); **Hyoungsub Choi**, Goyang-si (KR)
(73) Assignee: **SAMSUNG ELECTRONICS CO., LTD.**, Gyeonggi-do (KR)
(**) Term: **15 Years**
(21) Appl. No.: **29/681,742**
(22) Filed: **Feb. 27, 2019**

(30) **Foreign Application Priority Data**

(57) **CLAIM**

The ornamental design for a stand for cleaner, as shown and described.

DESCRIPTION

FIG. 1 is a front perspective view of a stand for cleaner, showing our new design;
FIG. 2 is a front view thereof;
FIG. 3 is a rear view thereof;
FIG. 4 is a left side view thereof;
FIG. 5 is a right side view thereof;
FIG. 6 is a top view thereof;
FIG. 7 is a bottom view thereof;
FIG. 8 is a rear perspective view thereof;
FIG. 9 is an enlarged view of the encircled portion 9 in FIG. 1;
FIG. 10 is an enlarged view of the encircled portion 10 in FIG. 1; and,
FIG. 11 is a front perspective view of the stand for cleaner of FIG. 1, shown with environmental structure.
The even-dash broken lines illustrating portions of the stand for cleaner and environmental structure form no part of the claimed design. The dot-dash broken lines encircling enlargement portions of the claimed design form no part of the claimed design.

1 Claim, 10 Drawing Sheets
